CLAIM

The ornamental design for a stylized pivot for scissor-action hand tool, as shown and described.

DESCRIPTION

FIG. 1 is a front left-perspective view of stylized pivot for scissor-action hand tool according to our new design;

FIG. 2 is a left side view of FIG. 1;

FIG. 3 is a bottom left-perspective view of FIG. 1;

FIG. 4 is a front right-perspective view of FIG. 1;

FIG. 5 is a right side view of FIG. 1;

FIG. 6 is a top right-perspective view of FIG. 1;

FIG. 7 is a top plan view of FIG. 1; and,

FIG. 8 is a bottom plan view of FIG. 1.

The dash-dash broken lines illustrate environmental structure and form no part of the claimed design.

Conventional shading and shadows are illustrated for purposes of highlighting the solid-rendering, but forms no part of the claimed design.
